US0D1047518S

(12) **United States Design Patent** (10) **Patent No.:** **US D1,047,518 S**
(45) **Date of Patent:** **** Oct. 22, 2024**

(54) **PILLOW**

(71) Applicant: **Texpack International Limited**,
Guangzhou (CN)

(72) Inventor: **Zeqin Zhang**, Guangzhou (CN)

(73) Assignee: **Texpack International Limited**

(**) Term: **15 Years**

(21) Appl. No.: **29/881,021**

(22) Filed: **Dec. 27, 2022**

(51) LOC (14) Cl. **06-09**

(52) U.S. Cl.

USPC **D6/601**
